ABSTRACT OF THE DISCLOSURE

A releasable latch having a pair of latch members one of which is carried by a movable lever normally urged in one direction and with the other urged toward engagement with the first member in which the first member is movable relative to the lever between positions where the first latch is in position to engage the second latch and a position where a cam forming a part of the first member holds the two latch members out of position for this engagement together with a catch that engages the combined first latch and cam member for successively moving the first member on successive movements of the lever, the successive movements of the first member being from one position where the catch members are positioned for engagement and another position where the cam member holds them out of engagement and then back to the first position.

The releasable latch of this invention provides for automatic moving of one combined latch member and cam between a position for engagement with a second latch member and a position where such engagement cannot be accomplished on successive movements of a lever on which the combined first latch and cam member is mounted. A latch of this type has been found particularly applicable to any type of device where the latch members are relatively inaccessible but where the lever is readily accessible. A unit of this type is disclosed in my copending application Ser. No. 637,177, filed May 9, 1967, and assigned to the same assignee as the present application.

One embodiment of the invention is illustrated in the accompanying drawings in which:

FIGURE 1 is a side elevational view partially in section and shortened of a combined floor scrubber and polisher employing the releasable latch of this invention.

FIGURE 2 is a fragmentary sectional view taken substantially along line 2—2 of FIGURE 1.

FIGURE 3 is an enlarged fragmentary sectional view taken substantially along line 3—3 of FIGURE 2.

FIGURES 4—8 are fragmentary side elevational views of a portion of FIGURE 3 showing the parts in different successive positions.

The floor scrubber and polisher shown in FIGURE 1 which carries the releasable latch of this invention is shown and described in greater detail in my above copending application. Generally, however, the device comprises a propelling handle 10 for propelling the device over a floor, a container 11 for liquids such as detergent solution and polish solution to be dispensed onto the floor as desired by operation of a valve control button 12, a motor 13, driven rotatable brush assembly 14, a floor contacting squeegee 15 for drawing water or cleaning solution from the floor after the cleaning operation has been performed and a releasable latch device 16 for either holding the squeegee 15 in elevated position, which would be up from that shown in FIGURE 1, or to permit it to be returned to floor contacting position as shown in FIGURE 1. As shown most clearly in FIGURE 3, the latch device 16 comprises a lever 17 having a foot pedal 18 thereon with the lever being arcuately movable about the longitudinal axis of a fulcrum part 19 held against any movement except this arcuate movement by a mounting

2

bracket 20 operating as a bearing. The lever end 21 that carries the foot pedal 18 is constantly urged in an upward direction as indicated by the arrow 22 in FIGURE 3.

The lever end 21 carries with it a combined first latch and cam member 23 that includes a first latch 24 in the form of a laterally projecting pin and opposite end cam surfaces 25. Located adjacent the first member 23 is a second latch member 26 that is adapted to be engaged by the latch pin when the first member 23 is in one position but not when it is in a second position.

The second latch member 26 is formed as a hook portion of a side flange on a spring metal arm 27 whose springiness urges the second member 26 to the left as viewed in FIGURES 3—8 and thus toward engagement with the first member 23. The first member 23 during movement of the lever 16 about its fulcrum portion 19 slides on a flat surface 28 on the spring arm 27. When the first member 23 is in the position shown in FIGURE 3, or turned 180° therefrom, the slide surfaces 29 are the long sides 29 of the first member 23. When the member 23 has been turned, however, either of the cam surfaces 25 will slide on the surface 28 as shown in FIGURE 5. In this position the dimensions of the first member 23 are such that the first latch member pin 24 is out of position to be engaged by the second latch member 26 as shown in FIGURE 5.

In order to turn the first member 23 about its axis which coincides with the axis of the latch pin 24 there is provided on the spring arm 27 beneath the second latch member 26 a catch member 30 in the form of a short tongue of metal of low height struck from spring arm 27. This catch member 30 is located a sufficient distance below the second latch member 26 that the end cam surfaces 25 will not engage it until the latch pin is well below the second latch member 26.

When the latch pin 24 and latch member 26 are in engagement, as shown in FIGURE 3, the squeegee 15 is retained in elevated position out of contact with the floor because the vertically movable end 21 of the lever 17 is held in its down position by latch 26 engaging pin 24. When it is desired to release the latch members from their FIGURE 3 engagement thereby raising lever 17 end to the position shown in FIGURE 6 so that the squeegee is returned to its position shown in FIGURE 1, it is merely necessary to depress the foot pedal portion 18 of the lever 16 downwardly from the position shown in FIGURE 3. When this is done the lowermost cam surface 25 engages the catch member 30 as shown in FIGURE 4 and momentarily holds it to turn the first member 23 to where this lowermost cam surface 25 rides on the catch 30. The width of this adjacent surface 25 is so much greater than the height of catch 30 that this adjacent surface 25 slides over the top of catch 30 to the position shown in FIGURE 5 upon gradual release of pressure on the foot pedal 18. The result is that this one of the two cam surfaces 25 bears against the flat surface 28 on the spring member 27 as shown in FIGURE 5. Then, when the foot pedal 18 is released further the lever 17 can move upwardly as indicated at 22 under the urging means, as previously described, without the second latch member 26 engaging the now out of position first latch member 24 which is in the position shown in FIGURE 5. Under the urging of the urging means 22 the lever 17 is moved to its greatest elevated position as shown in FIGURE 6.

When it is desired to again hold the squeegee 15 in elevated position the lever 17 is depressed by means of the foot pedal 18 from the position shown in FIGURE 6 to the position shown in FIGURE 7. When this occurs a side surface 29 of the first member 23 engages the catch member 30, as shown in FIGURE 7, to turn the first member 23 again through 90° until the corresponding

side surface 29 again bears against the flat surface 28 of the spring arm 27 and rides on the catch 30. Then, when the foot pedal 18 is again released the upward urging of the lever 17 causes the side surface 29 to slide over the catch 30 and the latch member pin 24 to again engage the second latch member 26, as shown in FIGURE 3.

As can be seen from the above description, the latch of this invention permits successively turning the first latch member 23 from one position where the latch pin is in position to be engaged by the second latch member 26 to another position where one or the other of the cam surfaces 25 bearing against arm 27 hold the latch members 23 and 26 apart as shown in FIGURE 5. Successive movements of the lever, therefore, move the first member 23 in successive latch and unlatch positions. Because this is done merely by movement of the lever 17 the two latch members may be, and in the illustrated embodiment are, completely hidden and inaccessible.

Having described my invention as related to the embodiment shown in the accompanying drawings, it is my intention that the invention be not limited by any of the details of description, unless otherwise specified, but rather be construed broadly within its spirit and scope as set out in the accompanying claims.

The embodiments of the invention in which an exclusive property or privilege is claimed is defined as follows:

1. A releasable latch, comprising: a movable lever normally urged in one direction; a combined first latch and cam member on said lever; means mounting said first member on said lever for movement with and relative to said lever; a second latch member; mounting means for urging said second latch member toward engagement with said first latch member, said first member when in one position on the lever locating its latch in position to be engaged by said second latch member under the urgings of said lever and said latter mounting means and when in

5 another position holding said second latch member out of position to be engaged by said first member; and a catch member on said latter mounting means located to be repeatedly engaged by said first member on successive movements of the lever past the second latch member and thereby moving said first member successively from said one position to said other position and back to said one position.

2. The latch of claim 1 wherein said latter mounting means comprises a spring arm on which both said second latch member and said catch member are located.

3. The latch of claim 2 wherein said first member moves on said first mentioned mounting means during said movements of said lever.

15 4. The latch of claim 3 wherein said first member is provided with latter mounting means engaging surface means holding said first member against movement relative to said lever except during said engagement with said catch member.
